TRACTION ATTACHMENT FOR SKIS

Doris Farmer, Montreal, Quebec, Canada, assignor to Ski Hill Climber Incorporated, Montreal, Quebec, Canada

Application June 8, 1939, Serial No. 278,121

5 Claims. (Cl. 280—11,13)

The present invention relates to improvements in traction attachments for skis.

An object of the invention is the provision of a traction attachment for skis which is highly effective to prevent back slipping of the ski.

Another object of the invention is the provision of a traction attachment for skis which may be quickly and easily disposed in operative or in inoperative arrangement.

10 A further object of the invention is the provision of an attachment of the above character having means for releasably holding a traction member in inoperative position and spring means tending to dispose the said member in an operative position.

Still another object of the invention is the provision of a traction attachment of the aforesaid character which may be readily attached to conventional skis.

20 A still further object of the invention is the provision of a traction attachment for skis which is relatively simple and durable in construction.

Other objects and advantages of the invention will become apparent as the description progresses.

In the accompanying drawing forming a part of this specification and in which like reference characters are employed to designate corresponding parts throughout the same:

30 Figure 1 is a top perspective view of the attachment secured on a ski.

Figure 2 is a fragmentary top plan view of the same.

35 Figure 3 is a section taken on the line 3—3 of Figure 2.

Figure 4 is a side elevational view showing the ski in down-hill position.

40 Figure 5 is a similar view showing a ski in hill-climbing position.

Figure 6 is a section taken on the line 6—6 of Figure 2, and

Figure 7 is an enlarged fragmentary section taken on the line 7—7 of Figure 5.

45 Referring to the drawing, wherein for the purpose of illustration is shown a preferred embodiment of the invention, S generally designates the intermediate fragmentary portion of a conventional ski having a foot-rest pad F secured thereon.

On the top or upper face of the ski S, preferably adjacent and in the rear of the foot pad F, is mounted a flat anchor-plate 10 of essentially rectangular elongated form having the width corresponding approximately to the width of the

ski. Adjacent the forward end the plate 10 is formed with a transversely extending ridge 11, of rectangular cross section, formed with a through bore 12. At a point spaced rearwardly from the ridge 11 the plate is provided with rectangular transversely projecting lugs 13 extending beyond the edges of the ski and formed at the top with longitudinally extending grooves. As shown to advantage at Figure 1, the plate 10 is firmly fastened on the ski by a plurality of 10 screws 14 extending through apertures therein and engaging the ski body.

5 In each end portion of the ridge bore 12 is removably mounted a pivot spindle 16 having an enlarged head 17 on its outer end of a diameter greater than the diameter of the bore and provided with an annular groove 18 adjacent its opposite inner end. Each of these spindles is secured so that a portion is arranged in the bore and an extension portion projects laterally of the plate member, as shown at Figure 7, by means of a screw 19.

15 In each end portion of the ridge bore 12 is pivotally supported a traction member 21 in the form of a rigid elongated strip, of metal or the like, shaped to form a transversely arranged sleeve 22 on its inner end rotatably fitted on the projecting portion of the spindle. The opposite outer end of each tongue 21 is rounded and tapered to form a sharp point 23 and the tongue is preferably bent transversely at a point adjacent the outer end to provide a blade portion 24 bent at an obtuse angle with the remaining body portion, as clearly illustrated at Figure 3.

20 On the projecting portion of each spindle 16 is pivotally supported a traction member 21 in the form of a rigid elongated strip, of metal or the like, shaped to form a transversely arranged sleeve 22 on its inner end rotatably fitted on the projecting portion of the spindle. The opposite outer end of each tongue 21 is rounded and tapered to form a sharp point 23 and the tongue is preferably bent transversely at a point adjacent the outer end to provide a blade portion 24 bent at an obtuse angle with the remaining body portion, as clearly illustrated at Figure 3.

25 To each side edge of the ski is secured an elongated bracket 26 fastened by screws 27 and formed at one end with a tapered shoulder 28 having an interiorly threaded hole and disposed approximately below the projecting portion of each spindle. On this shoulder is fastened an arm 29, in the form of an elongated strip of rigid material, such as metal, having an aperture adjacent the inner end through which is extended a pivot screw 30 fitted in the hole in the shoulder. This enables swinging movement of the arm 29 in a plane parallel with and slightly below the top face of the ski to be positioned in a rearwardly or in a forwardly extending position against the side of the ski. The arm is slightly 30 twisted transversely to provide a depending lip 30 at one longitudinal edge disposed to frictionally engage a groove 31 formed in the top longitudinal edge of the bracket 26 to lock the arm when it is arranged in a forwardly extending position.

- At each side of the anchor plate 10 is mounted an elongated leaf or strip spring 33 having an inner portion fitted in the groove in each lug 13 and rigidly fastened therein by a screw 34. These 5 springs extend longitudinally and are arranged so that their outer end portions will contact with the inner portions of the respective tongues 21 so that the springs tend to force the tongues downwardly to operative traction positions.
- 10 As illustrated in the drawing, the respective tongues 21 are mounted to swing about the spindles in a plane perpendicular to the planes of the top and bottom faces of the ski. When disposed in inoperative position, each of the arms 15 29 is swung to a rearwardly extending arrangement, as illustrated at Figures 3 and 4, to engage the bottom of the tongue and hold the same in a raised position above the bottom face of the ski and against the spring 21. To render the spring 20 more effective, a screw 35 is fitted in a hole in the tongue and provided with a relatively large head projecting from the top to contact with the outer end portion of the spring. Thus, the tongue is clamped between the arm and the 25 spring and is securely held in a non-interfering position for normal use of the ski, particularly on level or down-hill sliding.

When the skier is travelling up-hill the arms 29 are swung from the rearwardly directed to 30 forward positions locked against the forward extensions of the brackets 26 and releasing the tongues which are depressed or swung downwardly by the action of the springs thereon which dispose the tongues so that the points contact 35 with the snow or ice on which the ski is moved and prevent backward sliding thereof. When used on relatively soft snow, the tongues will dig quite deeply therein and assume positions at approximately right angles to the ski, as shown 40 at Figure 5, and are restrained from further forward movement by the shoulders 28 which the tongues contact.

Thus, this attachment provides a relatively simple and effective means for affording traction 45 against back sliding of the ski on snow or ice and is designed to enable very simple and rapid adjustment to dispose the tongues or gripping spurs in inoperative positions or to release the same for operative traction arrangement.

50 It is to be understood that the form of my invention herein shown and described is to be taken as a preferred example of the same, and that various changes as to the shape, size and arrangement of parts may be resorted to without departing from the spirit of the invention or 55 the scope of the subjoined claims.

Having thus described my invention, I claim:

1. A traction attachment for skis comprising

a plate adapted to be secured on the top face of a ski, a pair of pivot elements attached to and projecting transversely from the plate, a pair of elongated tongues pivotally connected with said pivot elements movable to operative 5 traction positions and to raised inoperative positions, a bracket adapted for connection with a ski at each side, an arm pivotally mounted on the bracket movable in a plane parallel with the top face of the ski and adapted to hold each 10 tongue in a raised inoperative position in one arrangement and to release the tongue in another arrangement, and spring means engageable with the tongues yieldingly acting to swing the tongues to downwardly operative positions. 15

2. A traction attachment for skis comprising a plate adapted to be secured on the top face of a ski, a pair of pivot elements attached to and projecting transversely from the plate, a pair of elongated tongues pivotally connected with 20 said pivot elements movable to operative traction positions and to raised inoperative positions, a bracket adapted for connection with a ski at each side, an arm pivotally mounted on the bracket movable in a plane parallel with the top 25 face of the ski and adapted to hold each tongue in a raised inoperative position in one arrangement and to release the tongue in another arrangement, and a pair of leaf-springs mounted on the plate engageable with the tongues to 30 yieldingly depress the same to downward operative positions.

3. In a traction device for a ski, a pivoted traction member, and an arm pivoted to swing in a plane at right angles to the pivoted movement 35 of the traction member operable to support the said traction member in inoperative position, and means for releasably locking the said arm in its retracted inoperative position.

4. In a traction device for a ski, a pivoted traction member, a bracket attached to the ski, an arm on the bracket operable to assume a supporting position longitudinally under the traction member and an oppositely extending retracted position, and means for releasably lock- 45 ing the arm with the bracket.

5. In a traction device for a ski, a traction member pivoted to swing in a plane at right angles to the plane of the ski, a bracket attached to the side of the ski, an arm on the 50 bracket mounted to swing in a plane parallel with the plane of the ski, the said arm being movable to a rearwardly directed position to support the traction member in inoperative arrangement and to a forwardly directed releasing position, and means for releasably locking the arm in its forwardly arranged position. 55

DORIS FARMER.
